UNITED STATES PATENT OFFICE.

DANIEL J. RUSSELL, OF PORTLAND, OREGON.

REGISTER.

No. 866,787.

Specification of Letters Patent.

Patented Sept. 24, 1907.

Application filed July 14, 1906. Serial No. 326,185.

To all whom it may concern:

Be it known that I, DANIEL J. RUSSELL, a resident of Portland, in the county of Multnomah and State of Oregon, have invented certain new and useful Improvements in Registers, of which the following is a full, clear, and exact description.

The invention relates to registers and more particularly to pocket-registers or those which can be conveniently carried about the person.

10 The invention designs to provide an improved register which is simple in construction and can be produced at a low cost and consists in the several novel features set forth and more particularly defined by claim at the conclusion hereof.

15 In the drawings: Figures 1 and 2 are side elevations showing the opposite faces of the register. Fig. 3 is an elevation on an enlarged scale, the rotary dial at one side of the register being removed to disclose the stepping-up mechanism for the register. Fig. 4 is a similar 20 view, the gear-disk on which the rotary dial is mounted being shown. Fig. 5 is a face view of the register showing the gear-train for operating the totalizer. Fig. 6 is a transverse section on line 6-6 of Fig. 3. Fig. 7 is a detail section on line 7-7 of Fig. 5. Fig. 8 is a 25 detail showing the spring for holding the dog which prevents retraction of the pinion which advances the adder.

The improved device is preferably constructed to be retained in a case similar in appearance and size to a 30 watchcase, comprising a circular body 12, a pendant 13, a revoluble crown 19, a bow 14, a bezel-ring 15 provided with a crystal 16 to form one face of the device, and a bezel-ring 17 provided with a crystal 18, which forms the other face of the device. These bezel- 35 rings are removably connected to the body in the usual manner, *e. g.*, by springing them into engagement with an annular surface on the body. A supporting-plate 20 is rigidly secured in the body by screws 21 and thereby several of the operating parts of the register 40 are sustained in suitable manner.

The register comprises a device for indicating and determining the amount to be registered. Preferably the setting device is actuated by crown 19. A totalizing device is provided which indicates the aggregate 45 amount of the registrations and is operated successively for each indication to indicate the total by a push-button or actuator 23. An arbor 24 journaled in the pendant 13 is provided at its inner end with a pinion 25. The crown, arbor 24 and pinion 25 are secured 50 against longitudinal movement in the case. A revoluble disk or dial-plate 26 is mounted in the case, being held in an annular seat or shoulder 27 by a friction-

ring 28 of thin sheet-metal which is held in place by the bezel-ring 17. The disk is provided at its outer edge with a series of gear-teeth 29 with which the pinion 25 engages and whereby the plate can be rotated in either direction in response to rotation of the crown. A dial 30 is secured to the outer face of plate 26 at one side of the case so as to be visible through crystal 18 and has indicated thereon numbers or other figures according to the particular purpose for which the register is to be used, that shown, being provided with amounts in multiples of five, ranging up to one dollar, and used more particularly for an expense-register. A fixed pointer 31 is secured to bezel-ring 17 so it will have a 60 fixed relation with respect to the case and will not rotate with dial 30, said dial 30, pointer 31 and their operative parts above described thus constituting an item indicating mechanism. Thus, when any desired amount is to be registered it is only necessary to rotate 65 the crown to bring the corresponding figures of the dial 30 into registration with the pointer 31. Disk 28 has cut therein a snail-shaped variable stop 34 for limiting the movement of the actuating-mechanism for the totalizer to effect registration corresponding to the indicated amount or quantity on dial 30. This stop is formed with a series of steps 34' arranged at graduated 70 distances with respect to the center of the dial so that by rotation of the dial either of the graduated steps may be brought into operative relation with respect to 75 the register actuating mechanism to cause corresponding registration. *e. g.*, if crown 19 is operated so "50" will be indicated on the dial 30, step 34 of the stop will be brought into position to limit the registration to corresponding amount. 80

The aggregate amount registered is indicated by a dial 35, exposed through crystal 16 and non-revolably secured between the body and bezel-ring 15, and which has unit-indicating numerals 36 near its outer edge and multiple-indicating numerals 37 arranged within the 90 unit series. A pointer 38 is secured to rotate with an arbor 39 and extends into position to indicate one of the unit series of numerals 36. Said arbor 39 is journaled in plate 20 and a bracket 40 secured to one face of the plate. A pointer 41 extends to the multiple series of numerals 37 and is secured to a sleeve 42 revolvably mounted on arbor 39. Each revolution of pointer 38 is carried to the multiple pointer 41 by a gear-train comprising a pinion 44 secured to arbor 39, a gear-wheel 45, a pinion 46 operated by gear-wheel 45, and a gear 47 95 rigidly secured to sleeve 42 to which pointer 41 is secured. A friction strip 48 prevents overthrow of the carrying train and pointer 41 when they are operated. Thus it will be seen that successive operations of the 100

unit-pointer 38 in the same direction will be carried to the pointer 41 so that the mechanism will indicate the aggregate amount of the registration.

The mechanism for operating the totalizing mechanism to correspond with the amount indicated by dial 30 and pointer 31 comprises a pinion 50 rigidly secured to arbor 39 and whereby the arbor will be operated. A longitudinally movable rack-bar 51 is provided with ratchet teeth adapted to engage the teeth of pinion 50 to rotate the pinion and its connected train in one direction only said dial 35, pointers 38 and 41 and their operative parts thus constituting a totalizing mechanism.

The ratchet-teeth of the pinion and rack-bar are formed to slip over each other during the retraction of the rack so that the arbor will not be reversely rotated during the retraction of the rack. To permit the rack 51 to slip over the teeth of pinion 50 during the return stroke, it is pivoted as at 52 to a carrier 53 and is held normally in engagement with the pinion by a spring 54. Thus a one-way or slip-connection is provided whereby the pinion will be operated in one direction only. The rack-carrier 53 is slidably mounted adjacent one face of supporting-plate 20 and has lugs 54 which straddle a guide-rod 55, fixedly secured by brackets 56 to the supporting-plate. The carrier is provided with a stud or abutment 57 adapted to engage the stop 34 to limit the movement of the rack or resilient advance of the registering mechanism to correspond with the indication of dial 30 and pointer 31, it being understood that either of the steps of said stop may be brought into operative relation with respect to said abutment as shown in Fig. 4, and thereby the extent of movement of the rack and the amount added will be determined. The stop is adapted to restrict the movement of the rack to correspond to the indication on the dial 30. A dog 58 pivoted as at 59 to the supporting plate, is held normally in engagement with the pinion 51 by a spring 60.

The actuator-button 23 is operatively connected to the rack-carrier 53 to impart movement thereto within the limits of abutment 57 and stop 34 by an arm 61 having a pin and slot-connection 62 with the rack-bar and pivoted as at 63 to the supporting-plate, a link 65 pivotally connected to a rocker-plate 66 which is pivoted to the supporting-plate as at 67 and to which is connected the inner end of a rod 68 to which the actuator button is secured. Spring 69 retracts the register actuating mechanism and holds it in normal position. One end of this spring is connected to rocker 66 and the other end to the supporting-plate. The operation of the register will be as follows: By turning the crown 19 the number or quantity to be added appearing on dial 30 can be brought into registration with pointer 31. The graduated stop 34 on the dial will then be in such position with respect to the stud 57 of the actuating-mechanism 55 to permit sufficient movement of the rack-bar and carrier to advance the totalizing mechanism correspondingly. By depressing actuator-button 23 the totalizing mechanism will be advanced a corresponding amount. The actuating mechanism will be restored to its normal position and in readiness for another operation by spring 69 upon release of button 23. The totalizing mechanism will be operated successively for each registration and show the aggregate amount of the registration.

The invention is not to be understood as restricted to the details set forth but may be modified by the skilled mechanic without departing from the spirit and scope of the invention. Manifestly the dials may be differently marked according to the use for which the register is designed.

Having thus described the invention, what I claim as new and desire to secure by Letters Patent, is:

1. In a pocket register, the combination of a case, a totalizing mechanism, and an item indicating mechanism embodying an internally graduated stop device, and a single means for variably operating said stop device. 75
2. In a pocket register, the combination of a totalizing mechanism, and an item indicating mechanism embodying a rotary internally graduated stop device, means for operating the same, and a dial operable with said stop device. 80
3. In a pocket register, the combination of a case a totalizing mechanism, and an item indicating mechanism embodying an internally graduated stop device, and a single means outside said case for operating said stop device. 85
4. In a pocket register, the combination of a totalizing mechanism embodying an abutment, and an item indicating mechanism embodying an internally graduated rotary stop device, a single means for rotating said stop device, and an indicator operable with said stop device. 90
5. In a pocket register, the combination of a totalizing mechanism embodying an abutment, and an item indicating mechanism embodying a graduated rotary stop device, means for rotating said stop device, a dial secured to rotate with said stop device, a fixed pointer, a gear wheel on said stop device, a pinion engaging said gear, and means for operating said pinion. 95
6. In a pocket register, the combination of a totalizing mechanism, an item indicating mechanism embodying an indicator plate, a stop device on said plate, a stationary pointer for said plate, a pinion engaging teeth on said plate, means for operating said pinion, and connections between said stop device and said totalizing mechanism. 100
7. In a pocket register, the combination of an item indicating mechanism comprising a circular dial plate provided with gear teeth and having a variable stop opening therein, and a pinion for shifting said plate, of a totalizing mechanism embodying a connection controlled in its movement by the position of said dial plate through the variable stop opening therein. 105
8. In a pocket register, the combination of a case, a totalizing mechanism embodying a dial plate secured in and exposed at one side of said case, and an item indicating mechanism comprising a dial plate mounted in and exposed at the other side of said case and revolvably held therein, and means for operating the latter device. 110
9. In a pocket register, the combination with a totalizing mechanism comprising a pinion, a longitudinally movable rack connected to said pinion, means for varying the extent of movement of said rack, and means for operating said rack, of item indicating mechanism comprising an internally graduated stop device, and means for indicating the amount to be registered. 115
10. In a pocket register, the combination with a totalizing mechanism comprising a pinion, a longitudinally movable rack having a one-way connection with said pinion, means for varying the extent of movement of said rack, and means for operating said rack, of item indicating mechanism comprising an internally graduated stop device, and means for indicating the amount to be registered. 120
11. In a pocket register, the combination of a case, a totalizing mechanism comprising a pinion, a longitudinally movable carrier, a rack pivotally connected to said carrier and having a one-way connection with said pinion, means for varying the extent of movement of said rack, and means for operating said rack, of item indicating mechanism comprising means for indicating the amount to be registered. 125
12. In a pocket register, the combination of a circular case, a pendant, a crown, a totalizing mechanism, an item

indicating mechanism comprising a variable stop device connected to and operated by said crown, and connections between said totalizing mechanism and said stop device.

13. In a pocket register, the combination with a case, a 5 totalizing mechanism, and an item indicating mechanism comprising a crown, an arbor connected to said crown, and a variable stop device connected to said arbor.

14. In a pocket register, the combination with a case, and a totalizing mechanism comprising a pinion and a rack 10 connected to said pinion, of an item indicating mechan-

ism comprising a pendant, a crown, and means controlled by said crown for indicating the amount to be registered, means controlled by the item-indicating mechanism for controlling the extent of movement of said rack, and means for operating said rack.
